WELL PUMP JACK

Jerry M. Nesbitt and John O. Andree, Wichita Falls, Tex., assignors to J. C. Halbert

Application October 31, 1938, Serial No. 237,958

5 Claims. (Cl. 308—21)

This invention relates to oil well equipment and has particular reference to pump jacks and more especially to pump jacks of the walking beam type.

The primary object of the invention is in the provision of a simplified construction for pump jacks which is made possible by departures from conventional construction as herein described.

Another object of the invention resides in the provision of a jack of the bearingless type which in operation normally maintains a straight line vertical movement of the polish rod and at the same time provides a device of this character in which the walking beam may easily be shifted as necessary in the pulling of the rods, or readjusting of the device after the rods have been replaced.

Yet another object of the invention resides in the provision of a construction for pump jacks in which there is no appreciable wear of the working parts and one in which lubrication is unnecessary for successful operation.

Further, the invention seeks to provide a rugged construction for a pump jack capable of being easily repaired, the only material ordinarily necessary for repairing being short sections of wire line.

Other and lesser objects will become manifest as the description proceeds taken in connection with the accompanying drawing wherein:

Figure 1 is an elevational view of the invention and illustrating the supporting frame or stand in vertical section.

Figure 2 is a plan view of the rocker construction employed in supporting the walking beam on the stand, and

Figure 3 is an elevational view of the rocker construction, taken on lines 3—3 of Figure 1.

Continuing with a more detailed description of the drawing, the numeral 1 designates the supporting frame or stand having a base 2 which is substantially rectangular in shape, as indicated in Figure 1. Upright legs 3 are provided at each of the corners of the base 2 and are inclined toward the center. At the upper ends and between two of the legs 3 there is secured an angle iron or bracket 4, as illustrated in cross section in Figure 1, which, in addition to serving as a cross member, is used for another purpose to be related as the description proceeds.

Other cross members 5 and 6 are likewise arranged between the upper ends of the legs 3 which support the bracket 4 and other of the legs 3 in such a manner that these members 5 and 6 are parallel with respect to each other as well

as being positioned at equal heights above the base 2 to define a horizontal plane. Moreover, the parallel members 5 and 6 are arranged, as illustrated in Figure 3, in such a manner that sides *a* and *b* of each extend upwardly, whereas the other sides *c* and *d* extend toward each other, the purpose of which is to provide a track for the rocker assembly 7 which operates thereon.

At the ends of the tracks 5 and 6 there are provided integral upright checks 8 and 9 which serve as stops for the rocker 7 if the latter should become disengaged from the attachment means which will be described.

The rocker assembly 7 is comprised of a pair of spaced cross members 10 and 11 laterally and rigidly secured, such as by welding, to the underside of the walking beam 12 which is positioned parallel to the tracks 5 and 6. At the outer ends of the cross members 10 and 11, depending arcs 13 and 14 are welded or otherwise secured for operation on the tracks 5 and 6, thus providing an oscillating support for the walking beam 12.

Between the cross members 10 and 11 of the rocker assembly 7 there are vertically disposed plates 15 and 16, illustrated in Figures 1 and 2, for making the assembly more rigid as well as providing anchors for wire lines 17 which are secured thereto by cable clamps 18. The wire lines 17 extend around the cross member 10 nearest the stops 8 and 9, under the arcs 13 and 14, and terminate in wire rope connectors, one of which is illustrated in Figure 1, and are threaded and adjustably attached to the bracket 4 by adjustment nuts 19. The wire lines 17 are for the purpose of yielding to the displacement of the center of oscillation of the beam, yet preventing rectilinear movement in a direction opposite the point of attachment of the lines and stand.

At the end *e* of the walking beam 12, opposite the bracket 4, there is positioned a mule head 20 which supports a mule head bridle 21 and in turn a polish rod 22, the connection between the last named elements being by means of a conventional polish rod adjuster 23, as illustrated in Figure 1. The other end *f* of the walking beam 12 is provided with another head 24 for supporting a counter balance or weight 25 which is connected thereto by means of a length of wire line.

Attached to the underside of the walking beam 12 intermediate the ends *e* and *f* and between the cross members 10 and 11 there is rigidly secured a down bar 26 which has at its lower end a shoe 27 for imparting an oscillating movement to the walking beam 12.

In operation the shoe 27 is connected to a reciprocating rod line 28 by means of a bridle 29 imparting, through the medium of the elements described, vertical rectilinear movement to the 5 polish rod 22 as well as to the counter balance 25.

Describing briefly the operation of the invention; the curves of the mule head face and of the arcs 13 and 14 are so calculated that as the beam 12 is rocked to displace the center of oscillation thereof forward, the resultant movement is a forward thrust of the beam toward the lowermost point as against a downward and inward movement if the beam were oscillated on a fixed fulcrum. The result is therefore, that there 10 would be no tendency of the cable 21 to divert from a strictly vertical plane. On the up stroke of the forward end of the beam, the curve of the mule head face is such as to compensate for displacement of the center of oscillation of the beam by moving along a given point in direct 15 alignment above the well, thus causing the line 21 to move undeviatingly in a vertical plane. The cables 17 prevent other than the required displacement of the oscillating point of the beam 20 for the described results.

Obviously, the curvature of the arcs 13 and 14, the height of the rocker assembly 7, and the length of the beam 12, determine the shapes of the heads 23 and 24, but in carrying out the 30 invention these components may be varied to meet different requirements and yet provide for the true alignment of the polish rod 22.

Manifestly, the structure herein shown and described is capable of considerable changes and modifications from time to time by those skilled 35 in the art and such changes and modifications as may be resorted to falling within the spirit and intent of the invention may also be considered as falling within the scope of the appended 40 claims.

What is claimed is:

1. In a pump jack having a stand and a walking beam, a bearing for said walking beam comprising an arcuate rocker attached to the said 45 walking beam, a pair of tracks defining a horizontal plane and forming an upperpart of the said stand for supporting the said rocker, whereby movement of the latter on said tracks will effect displacement of the center of oscillation of said 50 beam, and flexible lines connected to said stand

and said rocker for confining the said rocker for operation on the said tracks.

2. In a pump jack having a stand and a walking beam, a bearing for said walking beam comprising a pair of parallel tracks mounted on the 5 said stand, a rocker in fixed relation to and supporting the said beam, a pair of arcs forming a part of the said rocker for operation on the said tracks, and whereby the center of oscillation of said beam will be displaced, and flexible lines 10 connected to said stand and to said rocker for restricting the said rocker against rectilinear movement on the said tracks.

3. In a pump jack having a stand and a walking beam, a bearing for said walking beam comprising a pair of horizontal and parallel tracks mounted at the top of the said stand, a rocker for operation on the said tracks comprising a pair of spaced cross members attached to the said beam and depending arcs attached to the outer ends of 20 the said cross members, and a plurality of flexible lines attached to the said stand and the said rocker for preventing rectilinear movement in a direction opposite the attachment of the said 25 lines and the said stand.

4. In a well pump jack having a walking beam and supporting structure, a bearing for said walking beam comprising parallel tracks carried by said supporting structure on either side of the major axis of said beam, an arcuate rocker carried by said beam to roll upon said tracks, whereby to effect displacement of the center of oscillation of said beam, flexible lines for constraining said rocker to operate on said tracks to effect displacement of the operative end of said 30 beam and means to adjust said latter means.

5. A well pump jack having a walking beam and supporting structure, a bearing for said walking beam including parallel tracks carried by said supporting structure on either side of the 40 major axis of said beam, an arcuate rocker carried by said beam to bear upon said tracks, flexible lines for constraining said rocker to operate on said tracks to effect displacement of the operative end of said beam, means to adjust said latter means and a shoe suspended below said walking beam having a curved surface corresponding to that of said arcuate rocker.
